UNITED STATES PATENT OFFICE

PETER A. SOLEM, OF ROCKFORD, ILLINOIS

MOTOR-CONTROL BOX FOR SANDERS

Application filed April 18, 1927. Serial No. 184,606.

This invention relates to a motor control box adapted for use on a variety of multiple-motored machines but especially designed for use on drum type sanders for controlling the driving motors singly or collectively and to permit any one or more or all of the motors being started or stopped as desired.

The principal object of the invention is to provide a compact control box of economical and practical construction providing a main set of contacts arranged to be opened and closed separately or collectively so that all of the motors of the machine may be started and stopped individually or as a group, and an auxiliary set of related contacts arranged to be used when the main set of contacts are thrown out so that the motors may be controlled individually for what is known as "jogging" or "inching" in the sanding of wood work.

The invention further contemplates the provision in connection with the main contacts of individual push buttons for the various contacts for throwing out any one or more of the contacts separately, in order, for example, to stop any particular motor or motors, and the provision of a yoke for throwing all of the contacts in or out as a group, the yoke being operable preferably by means of a switch lever arranged to be set into either one of three positions, namely a "run" position, a "stop" position, and a "jog" position. In the run position all of the main contacts are thrown in except as they may be thrown out individually by use of the push buttons to stop certain motors; in the stop position all of the main contacts are thrown out but the lever when moved to this position will return of its own accord to the run position immediately upon being released, due to a cam action; and in the jog position of the lever all of the main contacts are held out and it is possible by use of the auxiliary contacts to control the motors separately for jogging.

The invention is illustrated in the accompanying drawing wherein:

Figure 1 is a front view of a motor control box made in accordance with the invention, 50 a part of the cover plate being broken away

to show the arrangement of contacts and the means for operating the same.

Fig. 2 is a longitudinal vertical section taken on the stepped line 2-2 of Fig. 1 looking in the direction indicated by the arrows. 55

Fig. 3 is a transverse vertical section taken on the line 3-3 of Fig. 1 looking in the direction of the arrows.

Fig. 4 is a circuit diagram.

The same reference numerals are applied to corresponding parts throughout the views.

The control box of the present invention, as stated above, is designed especially for use on sanding machines for controlling the driving motors for the drums and the driving motor for the endless feed bed. Thus, in a three drum machine, three motors designated A, B, and C, (Fig. 4) are required for the driving of the drums and a fourth motor D is required for the driving of the bed. By control of the motors A, B, and C singly or collectively the machine may be made in effect a one, two, or three drum machine as desired and by control of the motor D the bed may be started and stopped as desired. However the control box is also adaptable to use with other multiple-motored machines and it should not, therefore, be assumed that any limitation is imposed on the invention by reference to this one particular use to which the same has been applied. Before passing to a description of the control box it will be observed in Fig. 4 that the motors are of the 3-phase A. C. type and have starting boxes a, b, c, and d respectively, suitably of any standard type, as for example the well known magnetically operated type, with feeder connections with the transmission lines 5, 6, and 7.

Contacts 8 associated with terminals 9, hereinafter referred to as the main contacts, are arranged normally to complete circuits through terminals 10 by way of conductors 11 and 12 through the various motors. These contacts, as will presently appear, are arranged for operation either singly or collectively so that the motors may be started and stopped separately or as a group. Another set of contacts 13, hereinafter referred to as auxiliary contacts, are associated with terminals 14 and are arranged to be used

when the contacts 8 are thrown out. They control the motors so that they can be started and stopped separately for jogging or inching, in which the motor is given only a few turns at each start. These contacts complete circuits with the terminals 10 through the various motors by way of a feeder 15 connected with the line 7.

The control box, as shown in Figs. 1 to 3, 10 comprises a casing proper designated by the reference numeral 16, having a cover plate 17 fastened thereto as by means of screws 18. The contacts 8 and 13, along with their associated terminals 9 and 14 respectively and 15 the common terminal 10, are provided in banks on insulation blocks or panels 19 within the box and suitable provision is made for the lead-in wires so that the box may have proper electrical connections with the motors 20 when mounted on the frame of the machine, it being understood of course that the box will be placed at the operator's station within convenient reach for the proper control of the machine. The main contacts 8 are 25 spring-pressed into engagement with the underside of raised contact portions 20 provided on plates 21 electrically connected with the terminals 10. The auxiliary contacts 13 are spring-pressed out of engagement with 30 the contact portions 22 provided at the other end of the plates 21. The main contacts have leaf springs 23 provided in connection therewith the free ends of which engage the outer ends of levers 24 serving as fingers for 35 depressing the contacts out of engagement with the contact portions 20. The levers 24 are of insulation material and are pivotally mounted on a rod 25 carried in brackets 26 depending from the cover plate 17. The 40 levers 24 are arranged to be depressed against the action of the leaf springs 23 and also against the action of the spring pressure of the contacts 8 to open the contacts when it is desired to stop the motors associated therewith. Push buttons 27 are provided in line 45 with the outer ends of the levers 24 for the individual depression of said levers so as to stop and start any one or more of the motors as desired. Normally, of course, all of the 50 main contacts are closed and the motors are in operation. However the depression of any one or more of the buttons 27 will open the contacts and stop whichever motors are associated with these buttons. Provision is 55 also made whereby all of the contacts may be opened together to stop all of the motors simultaneously. For this purpose a yoke 28 is provided extending across all of the levers 24 as shown in Fig. 1 and pivoted as at 29 on the rod 25. The yoke 28 has pairs of spaced lugs 30 for engaging the sides of the levers 24 to hold the same in proper position with respect thereto. The yoke 28 is operated by a switch lever 31 pivoted by means of a stem 60 32 to the cover plate 17. The inner end of

the stem 32 has a cross-head 33 thereon which is V-shaped in cross-section, as most clearly appears in Fig. 2, for reception in a V-shaped groove 34 provided in the yoke 28. The head 33 fits in the groove 34 when the yoke is in raised position, that is, when all of the main contacts 8 are closed and the lever 31 is in its "run" position. However the movement of the lever 31 to the "stop" position turns the head 33 with reference to the groove 34 and the beveled faces thereof exert a cam action to force the yoke 28 inwardly against the action of the leaf springs 23 and against the spring pressure of the contacts 8 to open the latter. The movement from the run position to the stop position does not angularly displace the head 33 sufficiently with respect to the groove 34 to hold the yoke 28 against returning to its normal position, and the moment the lever 31 is released the cam action of the head 33 in the groove 34 causes the lever 31 to swing back to its run position and, of course, the contacts 8 are again closed. There is, however, a position in which the head 33 is disposed crosswise with respect to the groove 34 and will serve to hold the yoke 28 in its depressed position until the lever is moved back to the run position, or sufficiently close to it. This position of the lever is known as the "jog" position which, it will be noted, is approximately ninety degrees displaced from the run position. The reason for this provision will presently appear. As thus far described it will be manifest that the operator may momentarily stop the machine by swinging the lever 31 to the mid position and that, immediately upon the releasing of the lever, the same moves back to its run position and the machine is thrown back into operation. Also the operator may stop any motor as desired by simply depressing the proper button. The word "Stop" is therefore placed at the bank of buttons 27.

When the switch lever 31 is in the "jog" 110 position all of the main contacts are opened and the operator may then turn the motors over separately as much as desired. In jogging it is necessary that it be possible to stop the motors instantly when desired as the operation is usually only momentary. For this reason the auxiliary contacts 13 are normally out of engagement with the contact portions 22 and are arranged to be pressed into engagement by push buttons 34, the shanks 115 36 of which ride in direct engagement with the contacts as shown. The motors associated with the various contacts will be operated only so long as the contacts are held closed. For proper identification of the bank 120 of buttons 35 the word "Start" is placed adjacent thereto. It is, of course, possible for the operator to jog any one or more of the drum motors or the drive motor for the endless feed bed.

I claim:

1. In a control box, the combination of a plurality of terminals, contact portions for said terminals, contacts spring pressed normally in one direction relative to said contact portions, a plurality of levers pivotally mounted alongside one another with the free ends arranged to cooperate with the contacts to move the same against the spring pressure in the opposite direction relative to the contact portions, separate manually operable devices for operating said levers to operate any one or more of said contacts, a yoke member for engaging all of said levers to operate the same together, a manually rotatable switch lever, and a wedge-shaped cross-head arranged to be turned by said lever, said yoke member having a wedge-shaped groove provided therein for the reception of the cross-head in one position of said switch lever, said head being arranged to ride out of said groove in the movement of said lever and thereby communicate movement to the yoke.
2. In a control box suitable for controlling a plurality of motors, the combination of a plurality of terminals having contact portions, contacts spring pressed normally in one direction relative to said contact portions, a plurality of levers pivotally mounted alongside one another with the free ends arranged to cooperate with the contacts to move the same against the spring pressure in the opposite direction relative to the contact portions, a separate push button cooperating with each lever to operate the same whereby any one or more of said contacts are operable at will, a yoke member for engaging all of said levers so as to operate all of the contacts independently of the push buttons, and a single manually operable means for operating said yoke member.
3. In a control box suitable for controlling a plurality of motors, the combination of a plurality of terminals having contact portions, one set of contacts cooperating therewith, said terminals having other contact portions, another set of contacts cooperating therewith, the one set of contacts being spring pressed normally into engagement with the contact portions associated therewith and the other set of contacts being spring pressed out of engagement with the contact portions associated therewith, a separate push button for each of the first mentioned contacts for moving the same against the spring pressure thereof, a plurality of levers pivotally mounted alongside one another each having the free end thereof engaging one of the second named contacts, a separate push button cooperating with each lever to operate the same whereby any one or more of the second named contacts are operable at will, a yoke member for engaging all of said levers so as to operate all of the contacts independently of the push buttons,
- and a single manually operable means for operating said yoke member.
4. In a control box suitable for controlling a plurality of motors, the combination of a plurality of terminals having contact portions, one set of contacts cooperating therewith, said terminals having other contact portions, another set of contacts cooperating therewith, the one set of contacts being spring pressed normally into engagement with the contact portions associated therewith and the other set of contacts being spring pressed out of engagement with the contact portions associated therewith, a separate push button for each of the first mentioned contacts for moving the same against the spring pressure thereof, a plurality of levers pivotally mounted alongside one another each having the free end thereof engaging one of the second named contacts, a yoke member for engaging all of said levers so as to operate all of the contacts, and a single manually operable means for operating said yoke member.
5. In a control box suitable for controlling a plurality of motors, the combination of a plurality of terminals disposed in a row, said terminals having one set of contact portions disposed in one row and another set of contact portions disposed in another row, a set of contacts spring pressed out of engagement with the first set of contact portions, a row of start push buttons, one for each of said contacts for moving the same against the spring pressure into engagement with the contact portions, any one or more of the contacts being operable at a time, another set of contacts spring pressed into engagement with the other set of contact portions, a row of stop push buttons, one for each of the last named contacts for moving the same against the spring pressure out of engagement with the contact portions associated therewith, any one or more of said contacts being operable at a time, a plurality of levers pivotally mounted alongside one another with the outer ends thereof arranged for engagement with the last named contacts, a yoke member for engaging all of said levers to operate the same together whereby to disengage all of the last named contacts independently of operation of the last named push buttons, and a single manually operable means for operating the yoke member.
6. In a control box suitable for controlling a plurality of motors, the combination of a plurality of terminals disposed in a row, said terminals having one set of contact portions disposed in one row and another set of contact portions disposed in another row, a set of contacts spring pressed out of engagement with the first set of contact portions, a row of start push buttons, one for each of said contacts for moving the same against the spring pressure into engagement with the contact portions, any one or more of the contacts being operable at a time, another set of contacts spring pressed into engagement with the other set of contact portions, a row of stop push buttons, one for each of the last named contacts for moving the same against the spring pressure out of engagement with the contact portions associated therewith, any one or more of said contacts being operable at a time, a plurality of levers pivotally mounted alongside one another with the outer ends thereof arranged for engagement with the last named contacts, a yoke member for engaging all of said levers to operate the same together whereby to disengage all of the last named contacts independently of operation of the last named push buttons, and a single manually operable means for operating the yoke member.

tacts being operable at a time, another set of contacts spring pressed into engagement with the other set of contact portions, a row of stop push buttons, one for each of the last named contacts for moving the same against the spring pressure out of engagement with the contact portions associated therewith, any one or more of said contacts being operable at a time, a plurality of levers pivotally mounted alongside one another with the outer ends thereof arranged for engagement with the last named contacts, a yoke member for engaging all of said levers to operate the same together whereby to disengage all of the last named contacts independently of operation of the last named push buttons, and a single manually operable means for operating the yoke member, said last mentioned means comprising a manually rotatable switch member, and a cross-head arranged to be turned thereby and to cooperate with the yoke member, one of the two last mentioned members having a wedge-shaped groove provided therein and the other member having a wedge-shaped portion received in said groove and arranged in the turning of said cross-head to ride into and out of said groove whereby to communicate movement to the yoke member.

30. 7. In a control box for controlling a plurality of motors, the combination of a plurality of terminals disposed in a row, said terminals having one set of contact portions disposed in one row and another set of contact portions disposed in another row, a set of contacts spring pressed out of engagement with the first set of contact portions, a row of start push buttons, one for each of said contacts for moving the same against the spring pressure into engagement with the contact portions, any one or more of the contacts being operable at a time, another set of contacts spring pressed into engagement with the other set of contact portions, a plurality of levers pivotally mounted alongside one another with the outer ends thereof arranged for engagement with the last named contacts, a yoke member for engaging all of said levers to operate the same together whereby to disengage all of the last named contacts, and a single manually operable means for operating the yoke member.

55. 8. In a control box suitable for controlling a plurality of motors, the combination with a plurality of terminals having contact portions, a row of contacts cooperating with the contact portions and spring pressed normally in one direction relative thereto, a pivot rod disposed substantially parallel with the row of contacts, a plurality of levers pivotally mounted on said rod in spaced relation to one another with the free outer ends thereof arranged to cooperate with said contacts, there being one lever for each contact, a yoke pivotally mounted on said rod

and spanning all of said levers intermediate their ends, a single means cooperating with the yoke member to move the same and communicate movement to all of said levers simultaneously whereby to operate all of the contacts simultaneously, the last mentioned means being operable from one limit position to another whereby all of the levers are either raised or depressed, and a row of push buttons, one for each of said levers cooperating with the free ends of the levers whereby to depress any one or more of said levers at a time.

In witness of the foregoing I affix my signature.
